(57) **CLAIM**

The ornamental design for a lamp, as shown and described.

DESCRIPTION

FIG. 1 is a perspective view of a lamp, illustrating my new design;

FIG. 2 is a front elevational view of the lamp of FIG. 1;
FIG. 3 is a rear elevational view of the lamp of FIG. 1;
FIG. 4 is a left elevational view of the lamp of FIG. 1;
FIG. 5 is a right elevational view of the lamp of FIG. 1;
FIG. 6 is a top plan view of the lamp of FIG. 1;
FIG. 7 is a perspective view of a lamp according to another embodiment of the invention;
FIG. 8 is a front elevational view of the lamp of FIG. 7;
FIG. 9 is a rear elevational view of the lamp of FIG. 7;
FIG. 10 is a left elevational view of the lamp of FIG. 7;
FIG. 11 is a right elevational view of the lamp of FIG. 7; and,
FIG. 12 is a top plan view of the lamp of FIG. 7.

In the figures, the unshaded areas enclosed by broken lines form no part of the claim. All other broken lines represent environmental structure which also forms no part of the claim.

1 Claim, 10 Drawing Sheets
